UNITED STATES PATENT OFFICE

OTTO ANDERS, OF BERLIN, GERMANY, ASSIGNOR TO SIEMENS & HALSKE AKTIENGESELLSCHAFT, WERNERWERK, OF SIEMENSSTADT, NEAR BERLIN, GERMANY

TELEPHONE SYSTEM

Application filed July 11, 1927, Serial No. 204,681, and in Germany July 23, 1926.

The invention relates to a circuit arrangement for automatic telephone systems and subscribers' lines having different traffic facilities, the incoming calls of different values being dealt with by an operator.

The object of the invention is to enable subscribers having different traffic facilities to be connected to the same final selector of an automatic telephone exchange, in order to avoid having to provide special switches or groups of switches, to which are connected the subscribers entitled to certain calls, for example, main exchange calls, etc. To achieve this, according to the invention, the impulse sender at the operator's position is provided with switching means, which come into action and prevent the call being set up when an attempt is made to set up a connection between a line of a certain value (for example main exchange line) and a station not entitled to these connections. This arrangement is of particular importance for private branch exchanges, in which calls of different value (main exchange calls, calls over cross connecting lines, record lines, etc.) are dealt with by an operator of the branch exchange in setting up the connections for calls to the extension stations.

By way of example, the drawing shows diagrammatically a circuit arrangement according to the invention, in which the branch exchange operator is provided with a key set for setting up a connection over selecting devices, and this key set controls a number sender. Furthermore, by throwing a key, the number sender in the impulse circuit is replaced by a number dial or a device controlled by the latter. The number sender is only partially shown, thus by way of example only the switching means are shown that are used for preventing certain connections in conjunction with the row of keys for the tens selection, so that the blocking is effected in certain decades.

When a subscriber of the main exchange

makes a call over the trunk line zOA to a subscriber HTn of the private branch exchange, the branch exchange receives a calling signal, the calling lamp AL being lighted by the H relay when the relay A is energized. The operator then connects up her head set, which is not shown in the drawing, to the calling exchange line and ascertains the wanted subscriber. The connection to a calling exchange line is brought about by the operation of the speaking key Afr . Only a back contact of this key Afr is shown in the drawing, and this contact serves to bring down the relay H after connection has been made to the calling exchange line, whereupon the calling lamp AL is extinguished. On pressing the starting key At one winding of the number-sender-starter relay Z is energized. The Z contact prepares a circuit for the E relay. As soon as a units key of the number sender is pressed springs $E(Z)$ are closed, thereby closing the circuit of relay $E1$. Relay $E1$ operates and closes contacts $e1\text{ II}$, which closes the circuit of relay E . Relay E operates and starts the operation of the number sender. (The number sender is not shown. A suitable one is shown and described in detail in the German Patent No. 377,603 issued June 22, 1923). A relay (not shown) in the number sender closes contacts $2(Z)$ to provide a holding circuit for relay $E1$.

In the example shown, all subscribers not entitled to be connected to an exchange line are reached by pressing the tens keys 4-9, while the outgoing exchange lines are connected to the level O . The keys 4-9 are connected in parallel in the circuit of the relay ZU , the circuit of which is made dependent on the operation of the relay E and relay $R2$ (not shown). The relay E having been energized, having operated when the branch exchange operator pressed a key in the units row of keys after receiving a call over the main exchange line, the contacts $e\text{ III}$ are

also closed and a circuit for the ZU relay is prepared. If the calling subscriber requests to be connected to a limited facilities subscriber and the corresponding tens key is pressed, then the ZU relay is also operated over the actuated key, (one of the keys 4—9). This relay ZU opens the control circuit by opening the contact z_u I while the contact z_u III connects up a supervisory signal KL for the operator, thereby notifying the operator that the called subscriber is not entitled to be connected to a main exchange line. By means of her head set, the operator may then inform the calling party that the wanted subscriber cannot be reached.

Over certain lines (cross connecting lines) it shall be possible to reach all the subscribers of the branch exchange. For example, if the lighting of the lamp FL has notified the branch exchange operator that a call has arrived from a private distant exchange over a cross connecting line such as line ZpFA and a subscriber of the branch exchange is wanted, she presses the key FT which causes relay Z1 to operate over one winding and prepare a circuit for the relay E2 at contacts z_1 . The latter is operated as soon as the pressing of a units key has started up the number sender. The keys 1—9 can be effectively operated, so that impulse transmission can take place. Should however the private distance exchange ask for one of the exchange lines, which are connected to the level O, the pressing of the key O also causes the relay ZU to operate and to interrupt the impulse transmission in the manner described.

To render the service quite reliable, the operator's position can be provided with a number dial in addition to the number sender. In that case, the switching means and the circuit for positioning the final selector are placed under the control of the number dial by throwing the key US.

When the lighting of the lamp AL gives the branch exchange a call signal over an exchange line for the subscribers connected to the digits 4—9, who have limited facilities, the operator connects her head set to the calling main exchange line and asks who is the wanted subscriber. By actuating the starting key AT, a circuit is closed for one winding of the relay Z, which closes the contact z and so prepares a circuit for the relay E. During the forward rotation of the branch exchange operator's dial, off-normal contacts $e(N)$ close the circuit of the relay V, which at its three contacts controls the following circuits: The contacts v_1 (N) causes the relay E 1 to operate, hence the relay E is also operated over the contacts el II. At contacts v II the relay V 1 receives current over; earth, contact v II, back contacts v_1 II, wiper I of the auxiliary switch in position O, relay V 1, battery, earth. The back contacts v III open, thus preventing the relay interrupter

RU (not shown) being operated when the relay V 2 operates and closes the contact v II. As the relay V 1 has been operated and closed contacts v 1 III, the rotary magnet of the auxiliary switch receives current impulses over the impulsing contacts i 1 (N) during the return motion of the number dial. The rotary magnet operates and rotates the wipers of the auxiliary switch onto the contact corresponding to the number of impulses. At the same time these impulses are transmitted over the contact i (N) to the lifting magnet of the final selector (not shown), so that the latter is raised to a certain level. At the end of the train of impulses, the relay V falls back owing to the opening of the off-normal contacts e (N) of the number dial. The separation of contacts v II opens the circuit of the relay V 1, which therefore deenergizes, because the wiper I of the auxiliary switch has left its normal position O. Now if the grouping of subscribers, who are not entitled to access to certain lines (main exchange lines), be such that they are connected for example to the levels 4—9 of the final selector, then on dialling any of the numbers 4—9, the wipers of the auxiliary switch are also set onto one of the contacts 4—9, hence upon the release of the relay V 1, the relay ZU is energized, a locking circuit is closed and the further transmission of the impulses is prevented by the contact z_u I. The operation of the relay ZU furthermore causes a signal (lamp KL) to be connected up for the operator, to notify the latter that a subscriber has been asked for, who is not entitled to be connected to the main exchange line.

The operator then notifies this to the calling party and returns to the normal position all the devices taken into use. This is effected by pressing the key AZ. Thereby the relay V 2 is operated, namely over: earth, key AZ, contact v 1 II, wiper of the auxiliary switch, relay V 2, battery, earth. Over its contact v 2 I, the relay maintains itself energized independently of the key AZ. The closing of the contact v 2 II causes the rotary magnet of the auxiliary switch to receive impulses over wiper II of the auxiliary switch, contact v III, contact v 2 III and contact v 1 II until the wiper I reaches its normal position and the relay V 2 falls back.

On calling from a private distant exchange, the relay E 2 is energized as before described. Thereby blocking is only effected when a main exchange line connected to the level O is asked for.

What is claimed is:

1. In a telephone system, an automatic switch, a calling device for controlling the operation of said switch, means for connecting said calling device to said switch, and means operative independent of the operation of said switch and responsive to a setting operation of said calling device under certain pre-

- determined conditions, providing said setting operation is to a particular position, for preventing the operation of said switch.
2. In a telephone system, a calling device, 5 an automatic switch variably controlled in accordance with a plurality of settings of said calling device, and means operative independent of the operation of said switch and effective under certain predetermined conditions for disabling said calling device, providing a certain one of said settings is in accordance with a particular digit.
3. In a telephone system, a first and a second trunk line, an automatic switch for extending calls from either trunk line, a calling device for controlling the operation of said switch, and means operative independent of the operation of said switch and effective when a call is extended from one of said trunk 20 lines and ineffective when a call is extended from the other of said trunk lines and responsive to a setting operation of said calling device, providing said setting operation is in accordance with a particular digit, for preventing the extension of the call.
4. In a telephone system, a first and a second trunk line, automatic switches for extending calls from either trunk line, a calling device for controlling the operation of said switches in accordance with a plurality of settings, and means for disabling said calling device effective when a call is extended from one of said trunk lines providing one of said settings is in accordance with any one of a 30 particular set of digits, and effective only when a call is extended from the other of said trunk lines providing one of said settings is in accordance with a particular one of said set of digits.
- 40 5. In a telephone system, a first and a second trunk line, automatic switches for extending calls from either trunk line, a calling device for controlling the operation of said switches in accordance with a plurality of settings, means for disabling said calling device effective when a call is extended from one of said trunk lines providing one of said settings is in accordance with any one of a particular set of digits, and effective only when 45 a call is extended from the other of said trunk lines providing one of said settings is in accordance with a particular one of said set of digits, a signal, and means for operating said signal whenever said calling device is disabled.
- 55 6. In a telephone system, a first and a second trunk line, a calling device for sending impulses corresponding to a series of digits over either trunk line, and means for preventing the sending of impulses over one trunk line corresponding to any series in which one of the digits is a particular number, and for preventing the sending of impulses over the 60 other trunk line corresponding to any series
- in which said one of the digits is any of a particular plurality of numbers.
7. In a telephone system, an automatic switch, a calling device for sending a plurality of series of impulses to said automatic switch to operate the switch, an auxiliary switch and means for operating the same in accordance with one series of impulses sent to said automatic switch, and means controlled by said auxiliary switch providing it is operated to a certain position for disabling said calling device.
- 70 8. In a telephone system, a first and a second trunk line, a calling device for sending a plurality of series of impulses over either of said trunk lines, an auxiliary switch and means for operating the same in accordance with one series of impulses, means controlled by said switch providing it is operated to a certain position for disabling said calling device, and separate means for each trunk for determining to what certain position the switch must be operated to become effective.
- 80 9. In a telephone system in which calls from one exchange over trunk lines to another exchange are extended to the called subscribers' lines by means of automatic switches operated under the control of a calling device, digit registering means associated with the calling device for preventing the extension 90 of connections over certain of the trunk lines to certain of the subscribers' lines.
- 95 10. In a telephone system in which calls from one exchange over trunk lines to another exchange are extended to the called subscribers' lines by means of automatic switches operated under the control of a calling device, digit registering means associated with the calling device for preventing the extension of connections over certain of the trunk lines to certain of the subscribers' lines, and for preventing the extension of connections over certain other of the trunks lines to certain other lines.
- 100 11. In a telephone system, a trunk line, a calling device for sending series of impulses over said trunk line, an auxiliary switch and means for operating it during the sending of one series of impulses over said trunk line and in accordance with said one series, and means 110 controlled by said switch providing it is operated to a certain position for preventing the further sending of impulses over said trunk line.
- 115 12. In a telephone system, a trunk line, a calling device for sending series of impulses over said trunk line, an auxiliary switch and means for operating it during the sending of one series of impulses over said trunk line and in accordance with said one series, means 125 controlled by said switch providing it is operated to a certain position for preventing the further sending of impulses over said trunk line, and means for preventing the further operation of said switch during the further 130

sending of impulses over said trunk line when such further sending is not prevented.

13. In a telephone system, an automatic switch for extending a connection, a calling device having a dial, a set of impulse contacts in said calling device controlled by said dial for operating said switch, a register switch, and a second set of impulse contacts in said calling device controlled by said dial simultaneously with said first set for operating said register switch.

In witness whereof, I hereunto subscribe my name this 14th day of June, A. D. 1927.

OTTO ANDERS.
